(57) **CLAIM**

The ornamental design for a thin profile wipe dispensing container, substantially as shown and described.

DESCRIPTION

FIG. 1 is a top, front, left perspective view of a thin profile dispensing container showing our new design, shown with the lid in an open position;

FIG. 2 is a perspective view of FIG. 1 shown with the lid in a closed position;

FIG. 3 is a front elevational view thereof;

FIG. 4 is a rear elevational view thereof;

FIG. 5 is a left side elevational view thereof, the right side elevational view being a mirror image thereto; and,

FIG. 6 is a top plan view thereof.
